UNITED STATES PATENT OFFICE.

GEORGE HILLS, OF PLAINVILLE, CONNECTICUT.

CLOCK-STAND.

SPECIFICATION forming part of Letters Patent No. 268,890, dated December 12, 1882.

Application filed July 8, 1881. (No model.)

To all whom it may concern:

Be it known that I, GEORGE HILLS, of Plainville, in the county of Hartford and State of Connecticut, have invented certain new and 5 useful Improvements in Clock-Stands, of which the following is a specification.

My invention relates to improvements in clock-stands; and the objects of my improvements are, first, to produce a counting-room 10 or office clock with ink-wells that has a small base, and thereby presents a neat appearance and is very compact in form; second, to attach a pen-rack and pen-wiper holder to said base in a very compact and convenient form 15 and of neat appearance; third, to so mount the call-bell, upright, and clock that the gong of the call-bell may also answer for the alarm-bell in case an alarm-clock is attached to the upright; and, fourth, to so mount the clock 20 that it may be turned over, back uppermost, for the purpose of winding, and thereby render it unnecessary to move the clock-base and ink-wells, so that there is no danger of slopping over the ink, as there is in ordinary ink-well clocks that have to be moved for winding. 25 I attain these objects by the mechanism illustrated in the accompanying drawings, in which—

Figure 1 is a front elevation; Fig. 2, a plan view; Fig. 3, a rear elevation on a reduced scale, and Fig. 4 a side elevation.

A designates the base; B, the upright, which rises from the back part of said base; C, the swinging frame, in which the clock D is mounted; E, the ink-well or other receptacle supporting frames or holders, which are attached by screws or rivets to the two lower corners of the upright; F, an ordinary call-bell, mounted upon the middle portion of the base; and 35 G, the pen-wiper holder, supported on arms a, which arms are attached to the under side of the base, and, projecting forward therefrom, form a pen-rack.

The parts may be of any pleasing design, 40 and the clock may be of any ordinary kind, either with or without an alarm.

The ink-well holders E may be made to conform to any desired form of ink-well, either square, hexagonal, or octagonal, and they are 45 secured to depending arms of the upright, as shown most clearly in Fig. 3. They project

beyond the base upon each side and are just above it, and there is no part which projects sidewise beyond these frames.

The pen-wiper holder G may be of any desired design to hold a sponge or other pen-wiper, and I prefer to make it open on the lower side; but it may, if desired, be made in the form of a pair of jaws and attached in the position shown. By supporting it by the two 50 arms a a said arms, in connection with the front side of the base, form a neat pen-rack for holding several pens and pencils, which pen-rack is in such a position as not to be in the way.

The call-bell F is mounted between the ink-well holders and mainly in front of the upright B. The lower end of the upright has an opening, through which one side of the bell projects to the rear, as shown in Figs. 3 and 4. 55 When an alarm or a striking clock is supported on the upright the hammer b may project downward through a slot in the clock-case, and stand in such a position as to strike upon the outside of the gong of the call-bell F when 60 the hammer operates, thus making one bell answer a double purpose, and also I dispense with a special bell for the clock which it is often inconvenient to attach, and sometimes is 65 so attached as to present an awkward appearance.

The frame C, in which the clock D is placed, is hung upon pivots, preferably screws c, and the frame is provided with stop-lugs d, which, by coming in contact with the back of the upright, stop the frame in the desired position, preferably with the front face of the frame standing back a little, as shown. The frame C, above the pivots or screws c c, is widened out to form wings g g, to cover the upper ends 70 of the upright, as shown in Fig. 1. When it is desired to wind the clock the frame C is swung forward on its pivots until the wings g g come in contact with the front of the uprights and stop the clock in the position indicated by 75 broken lines in Fig. 4, when it may be conveniently wound by a person in front of the clock, the clock of course being of the style which winds at the back. Were it not for the swinging frame C, the clock would ordinarily be 80 turned about with the back to the person who is to wind it, which act in an ink-well clock

would be liable to slop over the ink, and in any case it is more convenient to swing the clock on the frame than it is to move it bodily, base and all. The whole arrangement is such as to bring the several parts into a very neat and compact form without rendering them inconvenient to use.

I claim as my invention—

1. The improved clock-stand, consisting of the base A, call-bell F, mounted on said base, the upright extending upward from the base in rear of the center of said bell, also having an opening opposite the bell, and adapted to receive and support a clock whose hammer ex-

tends downwardly in rear of the upright to the bell, substantially as described, and for the purpose specified.

2. The improved clock-stand, consisting of the base A, upright B, swinging frame C, for carrying the clock D, and suitable stops to limit the movement of the frame C and clock D, substantially as described, and for the purpose specified.

GEORGE HILLS.
